US00D779993S

(12) **United States Design Patent** (10) **Patent No.:** **US D779,993 S**
(45) **Date of Patent:** **** Feb. 28, 2017**

(54) **BAND**(71) Applicant: **Apple Inc.**, Cupertino, CA (US)

(72) Inventors: **Jody Akana**, San Francisco, CA (US); **Bartley K. Andre**, Palo Alto, CA (US); **Shota Aoyagi**, San Francisco, CA (US); **Anthony Michael Ashcroft**, San Francisco, CA (US); **Jeremy Bataillou**, San Francisco, CA (US); **Daniel J. Coster**, San Francisco, CA (US); **Daniele De Iuliis**, San Francisco, CA (US); **M. Evans Hankey**, San Francisco, CA (US); **Julian Hoenig**, San Francisco, CA (US); **Richard P. Howarth**, San Francisco, CA (US); **Jonathan P. Ive**, San Francisco, CA (US); **Duncan Robert Kerr**, San Francisco, CA (US); **Marc A. Newson**, London (GB); **Matthew Dean Rohrbach**, San Francisco, CA (US); **Peter Russell-Clarke**, San Francisco, CA (US); **Benjamin Andrew Shaffer**, San Jose, CA (US); **Mikael Silvanto**, San Francisco, CA (US); **Christopher J. Stringer**, Woodside, CA (US); **Eugene Antony Whang**, San Francisco, CA (US); **Rico Zörkendörfer**, San Francisco, CA (US)

(73) Assignee: **Apple Inc.**, Cupertino, CA (US)(***) Term: **15 Years**(21) Appl. No.: **29/555,889**(22) Filed: **Feb. 25, 2016****Related U.S. Application Data**

(63) Continuation of application No. 29/524,101, filed on Apr. 16, 2015, now Pat. No. Des. 750,525, which is a continuation of application No. 29/498,990, filed on Aug. 11, 2014, now Pat. No. Des. 727,197.

(57) CLAIM

The ornamental design for a band, as shown and described.

DESCRIPTION

FIG. 1 is a bottom front perspective view of a band showing the claimed design;

FIG. 2 is a bottom rear perspective view thereof;
FIG. 3 is a front view thereof;
FIG. 4 is a rear view thereof;
FIG. 5 is a left side view thereof;
FIG. 6 is a right side view thereof;
FIG. 7 is a top view thereof;
FIG. 8 is a bottom view thereof; and,
FIG. 9 is a perspective view thereof showing the band in an
environment in which it may be used.
The broken lines in the figures show portions of the band and
environment that form no part of the claimed design.
